ELECTRIC CIRCUIT BREAKER

Filed May 17, 1933

Fig. 1.

UNITED STATES PATENT OFFICE

1,957,213

ELECTRIC CIRCUIT BREAKER

Leland S. Hobson, Folcroft, Pa., assignor to
 General Electric Company, a corporation of
 New York

Application May 17, 1933, Serial No. 671,496

5 Claims. (Cl. 200—150)

My invention relates to electric circuit breakers, more particularly to the means for mechanically and electrically connecting the stationary contact adapter to the lead-in conductor of the 5 circuit breaker.

Heretofore the use in a circuit breaker of clamp unions or joints between the lead-in conductor stud and stationary contact adapter has frequently been the source of excessive heating of 10 the circuit breaker due to poor electrical connection between the adapter and lead-in conductor stud. These members, which are generally composed of copper, are sometimes separated at their 15 contact surfaces by an oxide film which, together with the low pressure per unit contact area produced by the clamping means, results in a comparatively high resistance union between said members. Such a high resistance union, particularly in heavy duty circuit breakers for handling 20 large currents, in turn results in excessive heating at the rated capacity of the circuit breaker. This is an extremely undesirable situation since the specifications for heavy duty circuit 25 breakers generally limit the circuit breaker to a definite temperature rise at its rated capacity.

My invention has for its principal object the provision of improved means effecting the mechanical and electrical connection between the lead-in conductor stud and stationary contact 30 adapter of a circuit breaker.

My invention will be more fully set forth in the following description referring to the accompanying drawing, and the features of novelty which characterize my invention will be pointed 35 out with particularity in the claims annexed to and forming a part of this specification.

Referring to the drawing, Fig. 1 is a fragmentary view, partly in section, of a circuit breaker embodying my invention; Fig. 2 is a detailed view, 40 partly in section, of partially assembled structure shown in Fig. 1, and Fig. 3 is a fragmentary view, partly in section, of another construction embodying my invention.

In Fig. 1 there is shown, by way of example, a 45 contact structure for an oil circuit breaker comprising a vertically movable bridging member 1 and stationary contacts 2 and 3 adapted to be engaged and interconnected by the bridging member in its elevated closed circuit position. 50 The aforesaid contact structure which is immersed in a suitable insulating liquid, as oil, is of a well known type wherein each stationary contact comprises a plurality of pairs of resiliently mounted finger contacts as indicated at 2' 55 and 3', respectively, which are engaged and

spread apart by the wedge-shaped (in transverse cross section) bridging member 1. The stationary contact structure likewise comprises a contact adapter 4 on which are suitably mounted 60 in conducting relation, as at 5, the aforesaid contact fingers. The adapter is formed as a bar or block of conducting material, as copper, and is mechanically supported by and electrically connected to the circuit breaker lead-in conductor 65

6 in a manner hereinafter described.

Each lead-in conductor 6 comprises a tubular conductor stud of copper, or the like, provided with an insulating sleeve 7 extending to the union with the adapter 4 which is provided with a member 8 forming a part thereof. The member 8 is 70 arranged to extend within and be secured to the lower end of the tubular conductor stud 6, the conductor stud and member 8 having screw-threaded engaging surfaces for the purpose as 75 illustrated.

For the purpose of effecting a tight mechanical union and a low resistance electrical connection between the adapter member 8 and the conductor stud 6, a slot 9 and a central aperture 10 are formed centrally and axially of the member 8. 80 The lower portion of the central aperture 10 is formed as a screw tap and the upper portion of the opening is flared to form a conical wedging surface 11 which coacts with a corresponding conical wedging surface 12 of an adjusting screw 85 13. The slot 9 provides sufficient resilience for the member 8 to be expanded by the adjusting screw into high pressure contact engagement with the conductor stud 6.

The adjusting screw 13 is in its normal position 90 as illustrated in Fig. 1. The connection and disconnection of the contact adapter with respect to the conductor stud is made apparent by Fig. 2. In connecting the aforesaid members the adjusting nut 13 is first started into the adapter 4, 95 after which the adapter with the adjusting nut is inserted and screwed into the lower end of the conductor stud. When the adapter 4 has been screwed to the correct contact position, the adjusting nut 13 is securely tightened by a socket wrench extending through the conductor stud. 100

It will be apparent that the expanding force on the member 8 due to the engaging conical surfaces 11 and 12 will be high, depending of course on the angle of the wedging surfaces, so that the 105 adapter is forced into high unit pressure engagement with the conductor stud. Furthermore, the coacting screw-threaded engaging surfaces tend to form in effect a plurality of high pressure line contact areas with the result that a very good 110

low resistance electrical connection is provided between the conductor stud and the stationary contact adapter.

In view of the comparatively low resistance at 5 the conductor stud and adapter union, there will be no tendency for the screw threads to heat excessively, and disconnection of the adapter for the purpose of repair or replacement is greatly facilitated.

10 In Fig. 3 a modified form of the above described arrangement is shown wherein the adjusting screw 20 coacts with a frustro-conical nut 21 within the adapter member 8, the screw 20 in the present case entering the member 8 from beneath through the bore 22. The nut 21 may obviously be forced into wedging engagement with the member 8 in the manner above described so as to expand the same into high pressure engagement with the conductor stud 6. The screw 20 is provided with the usual screw head 20' so that assembly and final tightening of the adapter unit is simplified.

15 As in the previous case, the screw 20 is first started from beneath into the adapter block, the nut 21 being seated within the recess defined by the wedging surface 11 so as to receive the threaded end of the screw 20. The adapter member 8 is then screwed into the conductor stud until the contact adapter is properly located. The assembly is completed by suitably 20 tightening the screw 20 as indicated at 20'. The above arrangement has obvious advantages, particularly where the lead-in conductor stud is of appreciable length.

25 30 35 In both constructions shown, it will be noted that proper adjustment of the adapter can be quite easily secured. These necessary adjustments include, first, proper height with respect to the movable bridging member. This is secured by turning the adapter in or out of the threads, depending on whether the adapter is to be raised or lowered. This adjustment is necessary in order to obtain the proper contact pressures on the electrically connecting said adapted to said component is the proper alinement of the adapter, which is readily secured by slight rotation of the adapter. This makes possible proper contact pressures on the entire group of stationary contact fingers. After the proper adjustments are completed, the adapter is effectively locked to the conductor stud in proper position by expanding the adapter 8 in the manner above described.

40 45 50 55 60 65 70 The mechanical connection between the conductor stud and adapter involves a number of advantages in circuit breaker construction including simplicity, compactness in design, mechanical strength and ruggedness, and low cost because of the use of less copper and the ease of assembly. Furthermore, the absence of clamping rings or couplings between the adapter and conductor stud enables the conductor stud to be insulated throughout its entire length as illustrated in Fig. 1. In view of the fact that the coupling means in the present instance is located, at least in part, within the conductor stud which extends through the circuit breaker cover, the overall length of the contact adapter and conductor stud may be comparatively limited. In other words, the contact adapter could be located nearer the metallic cover structure of the circuit breaker tank than the type of adapter wherein a comparatively wide external clamping ring forms the union between the conductor stud and adapter.

It should be understood that my invention is not limited to specific details of construction and arrangement thereof herein illustrated, and that changes and modifications may occur to one skilled in the art without departing from the 80 spirit of my invention.

What I claim as new and desire to secure by Letters Patent of the United States is:

1. In an electric circuit breaker including a tubular lead-in conductor stud and a stationary contact adapter, means for mechanically and electrically connecting said adapter to said conductor stud comprising a member forming part of said adapter extending into one end of said stud, and an adjustable wedging member positioned centrally of said adapter member for expanding the same into high pressure engagement with said conductor stud. 85 90

2. In an electric circuit breaker including a tubular lead-in conductor stud and a stationary contact adapter, means for mechanically and electrically connecting said adapter to said conductor stud comprising a member forming part of said adapter extending into one end of said stud, said member having a slot and an aperture extending axially and centrally thereof, and a wedging member positioned in said aperture for expanding said adapter member into high pressure engagement with said conductor stud. 95

3. In an electric circuit breaker including a tubular lead-in conductor stud and a stationary contact adapter, means forming an adjustable mechanical and electrical union between said adapter and stud comprising a member forming part of said adapter extending into said conductor stud and having screw-threaded engagement therewith, said member having a centrally disposed aperture, and a wedging member located within said aperture and adapted to engage said adapter member so as to extend said member into high pressure contact engagement with and to lock the same to said conductor stud. 105 110 115 120 125

4. In an electric circuit breaker including a tubular lead-in conductor stud and a stationary contact adapter, means forming a mechanical and electrical union between said stud and adapter comprising a member forming part of said adapter extending within said stud, said member and stud being in screw-threaded engagement, said member having a slot extending axially 125 thereof and a centrally disposed aperture terminating in a screw tap, and an adjusting wedging screw disposed within said aperture and coacting with said screw tap, said screw having a conical wedging surface coacting with a corresponding surface in said member for expanding said member into high pressure contact engagement with said stud. 130 135

5. In an electric circuit breaker including a tubular lead-in conductor stud and a stationary contact adapter, means forming an adjustable mechanical and electrical union between said stud and adapter comprising a member forming part of said adapter extending within one end of said stud, said adapter having a bore extending 140 centrally of said member, said bore terminating in a conical-shaped recess, a nut having a wedging surface corresponding to said conical recess and seated within said recess, and a screw extending through said bore and coacting with said nut 145 for expanding said adapter member into high pressure contact engagement with said stud.

LELAND S. HOBSON.

CERTIFICATE OF CORRECTION.

Patent No. 1,957,213.

May 1, 1934.

LELAND S. HOBSON.

It is hereby certified that error appears in the printed specification of the above numbered patent requiring correction as follows: Page 2, lines 44 and 45, strike out the words "electrically connecting said adapted to said component" and insert instead bridging member. The second essential adjustment; and that the said Letters Patent should be read with this correction therein that the same may conform to the record of the case in the Patent Office.

Signed and sealed this 19th day of June, A. D. 1934.

Bryan M. Battey

(Seal)

Acting Commissioner of Patents.
